United States Patent Office.

WATSON SANFORD, OF NEW YORK, N. Y.

Letters Patent No. 97,966, dated December 14, 1869; antedated September 3, 1869.

COAL-STOVE.

The Schedule referred to in these Letters Patent and making part of the same.

To all to whom these presents may come:

Be it known that I, WATSON SANFORD, of the city, county, and State of New York, have invented certain new and useful Improvements in Stoves; and I do hereby declare the following to be a full, clear, and exact description thereof, reference being had to the accompanying drawings, and to the figures and letters marked thereon.

Of these drawings—

Figure 1 is an elevation, with one-half of the stove in section.

Figure 2, a horizontal section, at the line $z z$ of fig. 1.

My invention consists—

First, in an improvement in the neck or portion of the stove between the fire-pot and body, consisting of a series of openings placed therein.

Second, in an improved combination and arrangement of the fire-pot and body, and contracted neck, either with or without a series of openings.

To enable those skilled in the art to construct and use my improvements, I will proceed to describe the same.

a is the fire-pot; *b* is a rim, extending inward, and to some extent, over such fire-pot, and may be either convex or flat.

The rim or ring so constructed causes the gases to reverberate, and to throw themselves back again on to the fire, consuming them more or less, and thereby causing greater heat and economy of fuel. Thus,

in such hemispherical fire-pot, the heat is compressed, retained, and reverberated, and is thereby intensified, whereas in the old straight pot, the gases are permitted to pass off, un retarded, to the chimney.

At the point of greatest contraction of this rim *b*, is a flange, *c*, which can be corrugated or perforated, shown as corrugated in the drawings, and thus permit of the introduction of oxygen to mix with the products of combustion, and insure a more perfect combustion by more thoroughly igniting them, and thereby producing a still further economy of fuel.

Above this contracted neck is the body, *d*, of the stove, constructed in an almost inverted form to the fire-pot, before described, as fully appears by the drawings, thus causing a second reverberation of the products of combustion, retaining them longer, and more thoroughly utilizing their component parts.

What I claim as new, and desire to secure by Letters Patent, is—

1. The arrangement of a series of openings in the neck, and between the fire-pot and the body of the stove, substantially as described.
2. The combination and arrangement of the body and fire-pot with the neck, with or without a series of openings, substantially as described.

WATSON SANFORD.
